UNITED STATES PATENT OFFICE.

MAX VON DER HEIDE, OF KIEL, GERMANY.

VALVE-CONTROL DEVICE.

Application filed April 6, 1925, Serial No. 21,092, and in Germany April 14, 1924.

This invention relates in general to valve control devices and more particularly to high pressure controlling valves for the automatic regulation of the gas required for breathing in breathing apparatus.

A known arrangement in breathing apparatus for regulating the supply of breathing gas required for the lungs of the user of the apparatus comprises two levers moved 10 in opposite directions for the purpose of controlling the admission of gas at a high pressure, which levers are placed in the breathing bag or in some other bag affected by the motions due to suction or inhalation. 15 In this known arrangement the fulcrums of the two levers are arranged above and below the valve closing body in the valve casing. A disadvantage of this arrangement is that the positioning of the fulcrums of the levers 20 relatively to the axis of the valve closing member cannot be chosen at will so that certain limitations are imposed which prevent the most favorable ratio being obtained between the power and load arms of 25 the levers for the greatest sensitiveness of the valve.

This invention constitutes a more favorable solution of this problem. It consists 30 in pivoting the levers in the axis of the sliding, spring-actuated, valve-closing member and in a space between the valve casing, or a part fixed to the same, and the valve closing member, and in providing cam surfaces 35 near the fulcrum or pivots of the levers by which the valve closing member is shifted axially against its spring when the levers are rotated or rocked in opposite directions.

The sensitiveness of the novel valve controlling arrangement can be increased by 40 placing a rolling member such as a ball between the co-operating cam surfaces. The co-operating or juxtaposed surfaces of the levers near their pivots may be provided for this purpose with recesses of gradually 45 increasing depths which are so shaped and located that the deepest parts of the two recesses of a cooperating pair of recesses register with each other when the levers are rocked in a certain position, while the shallow parts of the two recesses of a pair register with each other when said levers are turned into another position, and a ball is 50 located in each pair of recesses for moving the levers apart in the direction of the axis 55 of the valve closing member and for thus forcing said slide member away from the

valve seat when the shallow parts of a pair of recesses are caused to register with each other.

To enable the valve closing member to be 60 easily taken out of the valve casing, the levers may be pivoted on a part which is separate from the said member and does not interfere with its removal. To this end a sleeve that serves as a bearing or pivot 65 for said levers may be screwed into the valve casing, and the valve closing member may be arranged to slide in a bore of the said sleeve. An alternative arrangement 70 consists in forming the fluid conductor or valve seat as a pivot for the valve levers and in arranging the valve closing member so that it slides in a slide-way in the valve casing independently of the part of the valve seat 75 on which the levers are pivoted.

To reduce the resistance to be overcome in moving the levers, balls may be provided not only between the juxtaposed co-operated surfaces but also between the external surfaces of the levers and the surfaces in 80 the valve casing abutting on said external surfaces.

The invention is illustrated in the drawing in which Figs. 1 and 2 show a vertical and horizontal section respectively through a valve whose controlling levers are provided with co-operating gliding cam surfaces.

Figs. 3 and 4 represent respectively a vertical and a horizontal section through a 90 valve in which the co-operating surfaces of the valve controlling levers roll upon each other.

Figs. 5 and 6 are vertical sections through two further modifications in which the rotary movements of the valve controlling levers are translated into an axial or lateral shifting movement of the valve controlling member by means of co-operating pairs of recesses in the adjacently-positioned 95 surfaces of the levers.

Figs. 7 and 8 are side and sectional views respectively which show the form of said recesses.

As will be seen from Figs. 1 and 2 an axially or longitudinally displaceable valve closing member 2 is provided in the valve casing 1 and pressed by a spring 3 against the mouth of the gas outlet or nozzle 4. The valve controlling levers 5 and 6, which 105 project into a collapsible bag (not shown) in a well known manner, have ends that are 110

pivoted on the valve closing member 2 so that they may rotate around the same (in Fig. 1 the levers 5, 6 move towards and away from the observer).

In Figs. 1 and 2 the lever 5 is provided with a hub 7 and the end of this hub that extends towards the nozzle 4 has a number of radial openings 8 distributed around its periphery. These openings 8 together with small channels 9 in the valve closing member 2 form gas passages. The end of the hub 7 that extends towards the left forms a journal for the ring or hub 10 of the other lever 6. The hub 7 carries between the ring 10 and its shoulder a ring 11 fixed by means of a set screw 12. The valve closing spring 3 tends to press all of the said parts together by means of a shoulder on the valve closing member abutting upon the left hand end of said ring. The spring 3 also tends to press the right hand end of the hub 7 against the valve casing 1. The adjacent surfaces of the bearing ring 10 of the lever 6 and of the ring 11 are provided with cam surfaces 13, 14. When the levers 5 and 6 are in a certain position as shown, the cam surfaces 13, 14 lie side by side as shown in Fig. 2, but when the breathing bag, or lever-controlling bag, not shown in the drawing, collapses the levers 5 and 6 are rotated in opposite directions and the cams 13 and 14 ride onto one another, and as the right hand end of the hub 7 abuts upon the valve casing at the right the valve closing member 2 is displaced towards the left against the action of the spring 3 so that the valve nozzle 4 is opened.

In the modification shown in Figs. 3 and 4 the ends of the valve controlling levers 5 and 6 are pivoted on pins 16 and 17 that extend transversely in a longitudinal slot 15 in the valve closing member 2. The pivoted ends of the levers have rolling cam surfaces which co-operate with each other when the levers are rotated in opposite directions. The pin 16 is fixed in a sleeve 18 which is screwed into an external sleeve 20. The internal sleeve 18 has pins 19 which prevent it from turning in the valve casing 1. The pin 16 passes through longitudinal slots 22 in the valve closing member 2. By rotating the external sleeve 20 around the internal sleeve 18 by means of notches 21 in the circumference of the sleeve 20 the position of the fixed pin 16 can be displaced to the right or left and the stroke of the valve closing member 2, which is moved longitudinally by the oscillation of the arms 5 and 6, can thus be adjusted.

To enable the levers 5 and 6 to be easily mounted on their pins 16 and 17, they are provided with lateral slots 23 and 24 respectively. The levers may be secured on their pins 16 and 17 by means of screws 25 and 26, although this is not absolutely necessary,

because the pressure of the valve closing spring 3 will prevent the levers 5 and 6 from slipping off their pins 16 and 17 in any case.

It is obvious that it is sufficient to oscillate only one of the levers 5 or 6 to cause a displacement of the valve closing member 2 for the purpose of opening the valve. Hence the laterally displaceable lever 6 could be replaced by a roller.

In distinction from the bearing arrangement of the levers 5 and 6 in Figs. 1 and 2, the bearing rings 27 and 28 of the levers in the modification shown in Fig. 5 are journalled on a sleeve 29 screwed into the casing 1, and in the modification shown in Fig. 6 the bearing rings of the levers are journalled on the end of the nozzle 4 so as to be rotatable and laterally displaceable thereon. The adjacent co-operating surfaces of the bearing rings 27, 28 are each provided with three recesses 30 disposed on a circle concentric to the centre of the valve closing member, these recesses being displaced with respect to each other by 120 degrees. The depths of the recesses decrease in the direction of rotation opposite to that in which the levers are turned around the valve closing member 2 when the valve is to be opened. The three recesses in the two adjacent surfaces of the levers 5 and 6 form three pairs of recesses in each of which there is a ball 32. When the levers are rotated so that the deepest parts of a pair of recesses register with each other the ball 32 sinks into the recesses under the action of the valve closing spring, and the valve is then closed. When the levers 5 and 6 are rotated in the opposite direction, the shallow parts of each pair of recesses register with each other and the balls then cause the bearing ring 27 to be laterally displaced so that the valve closing member 2 is shifted against the action of the spring 3 because the bearing ring 28 in Fig. 5 abuts upon a fixed shoulder 34 on the sleeve 29 screwed into the casing 1, and in Fig. 6 the bearing ring 28 abuts upon a washer secured upon the nozzle 4. In Fig. 8 the co-operation of the balls 32 and of the recesses 30 of gradually increasing depths in the adjacent surfaces of the bearing rings 27 and 28 is illustrated. The arrows in this figure show the direction of rotation of the bearing rings when the levers 5 and 6 are rotated to close the valve. This movement of the levers takes place when the breathing bag is expanded by the admission of oxygen from the oxygen container and the levers are released to allow the spring 3 to close the valve.

In order to further reduce the resistance offered by the levers and co-operating parts balls 36 are provided in Fig. 5 between the bearing ring 28 and the collar 34 of the sleeve 29 and further balls are placed be-

tween the bearing ring 27 and the abutting surface 35 of the valve closing member 2. A similar arrangement is provided in Fig. 6 except that the member 37 which corresponds to the part 2 in Fig. 1 does not itself close the nozzle 4 but is provided with an axially movable stopper 38 whose stroke can be adjusted by means of a threaded recessed ring 39, the valve closing spring 3 pressing 10 against the bottom of the recess.

I claim:

1. Valve control device of the kind described comprising a body with a valve closing member arranged to slide therein, a 15 spring for pressing the valve-closing member into its valve-closing position, rocking levers having their pivotal axes arranged substantially in the central portion of said slide member, and co-operating surfaces on 20 said levers for shifting said member into its valve-opening position when the levers are rocked in opposite directions.

2. Valve control device of the kind described comprising a casing and a valve seat 25 therein, a slide member slidingly disposed in said casing to co-operate with the valve seat, a spring for forcing said slide member onto said valve seat, rocking levers having their pivotal axes arranged substantially in 30 the central portion of said slide member, and cam surfaces on said levers for shifting said slide member away from said valve seat when the levers are rocked in opposite directions.

3. Valve control device of the kind described comprising a valve casing with a valve seat therein, a sleeve fixed in said valve casing, a slide member in said sleeve, a 35 spring for forcing said member onto said valve seat, levers pivoted on said sleeve and having pairs of co-operating recesses of gradually increasing depths near their pivots, said recesses being of such shape and location that the deepest parts of two recesses of a pair register with each other when said levers are rotated to a certain position, while the shallow parts of two recesses of a pair register with each other when 40 said levers are moved into another position, and a ball located in each pair of recesses for moving the levers apart and forcing said slide member away from said valve seat when the shallow parts of a pair of said recesses are caused to register with each other, and balls arranged between said 45 external and abutting surfaces.

slide member away from said valve seat when the shallow parts of a pair of said recesses are caused to register with each other.

4. Valve control device of the kind described comprising a casing, a fluid conductor with a valve seat fixed in said casing, a slide member slidingly arranged in the casing in the axis of the bore of the fluid conductor, a spring for forcing the slide member onto said valve seat, levers pivoted to rotate round said axis and having pairs of co-operating recesses of gradually increasing depths near their pivots, said recesses being of such shape and location that the deepest parts of two recesses of a pair register with each other when said levers are rotated in a certain position, while the shallow parts of two recesses of a pair register with each other when said levers are moved into another position, and a ball located in each pair of recesses for moving the levers apart and forcing said slide member away from said valve seat when the shallow parts of a pair of said recesses are caused to register with each other.

5. Valve control device of the kind described comprising a casing with a slide way and a valve seat therein, a slide member arranged in said slide way to co-operate with the valve seat, a spring for forcing said slide member onto said valve seat, levers pivoted in the axis of said slide member and having external surfaces and adjacently-positioned interacting surfaces provided with pairs of recesses of gradually increasing depths and of such shape and location that the deepest parts of the two recesses of a co-operating pair of recesses register with each other when the said levers are rocked to a certain position, while the shallow parts of two recesses of a pair register with each other when said levers are moved into another position, a ball located in each pair of recesses for moving the levers apart and forcing said slide member away from said valve seat when the shallow parts of a pair of said recesses are caused to register with each other, and balls arranged between said 50 external and abutting surfaces.

In testimony whereof I affix my signature.

MAX VON DER HEIDE.
